(57) **CLAIM**

The ornamental design for a deck-mount faucet, as shown and described.

DESCRIPTION

FIG. 1 is a top, front, right-side perspective view of a deck-mount faucet showing my new design;

FIG. 2 is a front elevational view thereof;

FIG. 3 is a right side elevational view thereof;

FIG. 4 is a top plan view thereof;

FIG. 5 is a left side elevational view thereof; and,

FIG. 6 is a rear elevational view thereof, the bottom, not seen in use, being plain and unornamented.
